Henry Williams.

UNITED STATES PATENT OFFICE.

FRANCIS E. CHERRIER, OF FITCHBURG, MASSACHUSETTS, ASSIGNOR OF ONE-HALF TO WILLIAM E. PUTNEY, OF SAME PLACE.

WHIFFLETREE-COUPING.

SPECIFICATION forming part of Letters Patent No. 391,021, dated October 16, 1888.

Application filed July 6, 1888. Serial No. 279,163. (No model.)

To all whom it may concern:

Be it known that I, FRANCIS E. CHERRIER, of Fitchburg, in the county of Worcester and State of Massachusetts, have invented new and useful Improvements in Whiffletree-Couplings, of which the following is a specification.

The object of this invention is to construct a whiffletree coupling without weakening the whiffletree by passing a bolt through it, and to produce a strong, reliable, and efficient coupling which will not rattle or shake.

The nature of the invention is fully described below and illustrated in the accompanying drawings, in which—

15 Figure 1 is a view in perspective of a whiffletree coupling embodying my invention. Fig. 2 is a transverse section of the same. Fig. 3 is a plan view of the under side of that portion of the coupling which is attached to the 20 whiffletree. Fig. 4 is a plan view of the upper side of that portion of the coupling which is attached to the cross-bar.

Similar letters of reference indicate like parts.

25 A represents the cross bar extending from one shaft to the other.

B is the whiffletree.

C is a metallic plate screwed to the upper side of the cross-bar and formed up into a circular box, C', with four inwardly-projecting lips, C''. Upon the bottom of this box is laid a packing, c.

30 D is a metallic plate screwed to the under side of the whiffletree and formed up into a central circular block, D', provided with four radial legs, D''. By means of the extra number of legs (two being the usual number) and lips there is always a full bearing-surface, however much the whiffletree is turned, and the packing, which is of appreciable thickness, as will be seen by the space in Fig. 2 left for it, effectually prevents rattling and endwise rocking.

35 E is a plate screwed to the under side of the cross-bar, and having its portion E' bent at right angles against the rear side of said cross-bar. From this portion is bent the broad lip E'', in which is cut a curved slot, e. The portion E of this plate is centrally perforated, and the bolt H passes through this perforation and

40 through the central perforation, h', in the plate C into the threaded hole h' in the block D'. The bolt does not pass through the whiffletree, but leaves it intact, being held by the metallic block above named.

I is a tie-strap or back-stay. This is a metallic rod of substantially the shape shown, one end, I', of which is threaded and extends through a slot, d, in the extension D'' of the plate in front of the whiffletree, and the other end, I'', of which is threaded and extends 55 through the curved slot e in the portion E'' of the plate E. The two ends of the tie-strap are held by suitable nuts, a and b. A branch, I''', integral with the main portion I, extends down close to and back of the whiffletree, as shown, 60 and by means of its T-shaped end I''' catches under parallel projections d', extending from the plate D, said projections being bent downward at their ends to prevent the T-shaped end from slipping out. A cross piece, i, extends at right angles from the tie-strap on the upper side of the whiffletree, but is not essential to the invention. As the whiffletree turns, the end I'' of the tie-strap moves in the arc of a circle in the slot e, while the plate containing said slot effectually prevents the whiffletree from drawing forward and down. Practically the coupling is doubly locked, and the whiffletree is not weakened by the passage of a bolt through it. 65

Having thus fully described my invention, what I claim, and desire to secure by Letters Patent, is—

1. In a whiffletree coupling, the combination of the cross-bar provided with the plate E E' E'', slotted on a curve at e, the whiffletree provided with the plate D, having the projections d' d'' and slotted at d, and the tie-strap I, its main portion extending from the slot d over the whiffletree to the slot e, said 70 tie-strap being provided with the branch I''', substantially as and for the purpose set forth. 75

2. In a whiffletree-coupling, the combination of the cross-bar provided with the plate E E' E'', slotted on a curve at e, and the plate C, centrally perforated, and provided with the box C', having the lips C'' and packing c, the whiffletree provided with the plate D, having the central hole, h', block D', legs D'', perforation d, and projections d', the tie-strap I I''', 80 and bolt H, all substantially as and for the purpose described. 85

FRANCIS E. CHERRIER.
